[57] CLAIM

The ornamental design for a shingle digger, as shown and described.

DESCRIPTION

FIG. 1 is a top plan view of my new design of a shingle digger;

FIG. 2 is a front elevational view;

FIG. 3 is a rear elevational view;

FIG. 4 is a left side elevational view; and

FIG. 5 is a bottom plan view.

The right side elevational view is substantially a mirror-image of the left side elevational view illustrated in FIG. 4.

The handle is shown broken away in FIG. 4 in the center in order to indicate that it has an indeterminate length.
